CLAIM

The ornamental design for a pet scratcher, substantially as shown and described.

DESCRIPTION

FIG. 1 is a left side elevation view of a first version of the pet scratcher showing the new design;

FIG. 2 is a right side elevation view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a front perspective view thereof;

FIG. 8 is a left side elevation view of a second version of the pet scratcher showing the new design;

FIG. 9 is a right side elevation view thereof;

FIG. 10 is a rear elevation view thereof;

FIG. 11 is a front elevation view thereof;

FIG. 12 is a top plan view thereof;

FIG. 13 is a bottom plan view thereof; and,

FIG. 14 is a front perspective view thereof.

The use of a separation and a bracket in FIG. 1-FIG. 7 indicates that the precise length of the pet scratcher is not
